UNITED STATES PATENT OFFICE

ERNEST C. HEAD, OF ROCHESTER, NEW YORK, ASSIGNOR TO GLEASON WORKS, OF ROCHESTER, NEW YORK, A CORPORATION OF NEW YORK

GEAR CUTTER

Application filed June 8, 1929. Serial No. 369,289.

The present invention relates to gear cutters and particularly to gear cutters of the face mill type such as are used in the cutting of spiral bevel and hypoid gears.

5 The present invention has for its primary purpose to make it possible to obtain an extremely accurate cutter. Other objects of the invention are to provide a construction which is convenient for adjustment and which permits the blades to be trued up on the cutter head quickly. Still other objects 10 of the invention will be apparent hereinafter from the specification and from the recital of the appended claims.

15 Several different embodiments of the invention are illustrated in the accompanying drawings in which:

Figure 1 is a plan view of a face mill gear cutter constructed according to one embodiment of the invention;

20 Figure 2 is a section on the line 2—2 of Figure 1;

Figure 3 is a plan view of a modified form of cutter;

25 Figure 4 is a section through this cutter taken on the line 4—4 of Figure 3;

Figure 5 is a sectional view on an enlarged scale taken on the line 5—5 of Figure 3;

30 Figure 6 is a fragmentary plan view of a cutter constructed according to another modification of this invention;

Figure 7 is a sectional view taken on the line 7—7 of Figure 6;

35 Figure 8 is a fragmentary plan view of still another modification of this invention;

Figure 9 is a section taken on the line 9—9 of Figure 8;

40 Figure 10 is a fragmentary sectional view taken radially of a cutter constructed according to a further modification of this invention;

Figure 11 is a sectional view of the same cutter taken at right angles to Figure 10;

45 Figure 12 is a fragmentary plan view of a cutter constructed according to another modification of this invention;

Figure 13 is a section through this cutter taken on the line 13—13 of Figure 12;

50 Figure 14 is a section taken on the line 14—14 of Figure 12;

Figure 15 is a section on the line 15—15 of Figure 17;

Figure 16 is a fragmentary plan view of a cutter constructed according to a still further modification of this invention; 55

Figure 17 is a sectional view of this cutter taken on the line 17—17 of Figure 16;

Figure 18 is a corresponding sectional view taken radially of a cutter constructed according to a still further modification of this 60 invention;

Figure 19 is a fragmentary plan view of a cutter constructed according to another embodiment of this invention;

Figure 20 is a sectional view on an enlarged 65 scale taken on the line 20—20 of Figure 19;

Figure 21 is a section on the line 21—21 of Figure 19;

Figure 22 is a fragmentary sectional view of a still further modification of this invention; 70

Figure 23 is a sectional view on an enlarged scale taken on the line 23—23 of Figure 22; and

Figure 24 is a section taken on the line 75 24—24 of Figure 22.

Referring first to the form shown in Figures 1 and 2, 30 designates the cutter head. This head is provided with a plurality of equi-spaced radial slots in which are adjustably mounted the blocks 31 which serve to carry the cutting blades 32. The blades 32 have a cutting portion 33 and a body portion 34. The cutting portion 33 extends beyond the blocks 31 and the adjacent side face of the cutter head in the direction of the axis of the cutter head. The cutting portions 33 are formed in the usual or any suitable manner, being relieved at the tip and on the sides back of the cutting edge or edges. In the drawings, all of the blades 32 are inside blades, that is, are provided with inside cutting edges. It is to be understood, however, that alternate blades might be provided with outside cutting edges or each blade might be formed so as to have both inside and outside cutting edges.

90 The body portion 34 of the blade is in the form of a cylindrical stud integral with the cutting portion 33, and is of reduced size to 95 100

provide a shoulder 35 between the cutting portion 33 and the stud 34. The shoulder 35 is preferably made circular in shape and fits into a correspondingly shaped recess formed 5 in the upper face of the block 31 while the stud 34 passes through a hole formed in the block. Each blade 33 is held in position in its block by a nut 36 that threads onto the lower end of the stud 34 and serves to draw 10 the shoulder 35 down firmly into its recess in the block 31.

The blade 32 is very simple to make and because of the shape of the stud 34 and shoulder 35 can be adjusted angularly on its block 31 15 to permit using the cutter in an intermittent indexing process as is the cutter of the patent to James E. Gleason, No. 1,236,834 of August 14, 1917, or in a continuous indexing process, as is the cutter of the patent to James E. 20 Gleason No. 1,249,378 of December 11, 1917.

The blocks 31 may be adjusted radially on the cutter head by means of screws 40, only one of which is shown in Figure 1. These screws 40 thread into the cutter head alongside of the blocks 31 and the heads 41 of the screws engage in kerfs or recesses 42 formed in the sides of the blocks 31. As shown in Figure 1, it is preferable to provide each block 31 with two kerfs or recesses 42 so as to 25 permit interchangeable manufacture and enable each block 31 to carry either an outside or an inside cutting blade. The blocks 31 are secured in any adjusted position by means of the bolts 43 and washers 44, the stems of the 30 bolts passing through slots 45 formed in the blocks 31 and threading into the cutter head and the heads of the bolts being received in countersunk slots 46 formed in the blocks 31. The cutter head 30 can be secured to the cutter 35 spindle 48 by means of a bolt 49.

The blades of face mill gear cutter are relieved on grinding machines built especially for that purpose and the greatest care is exercised to insure that the proper pressure angle 45 will be ground on the relieved blades. Difficulty is sometimes experienced, however, in setting up the blades in the cutter head in positioning the blades so that the correct pressure angle will be maintained in the assembled cutter. Figures 3 to 5 represent a form 50 of this invention which is preferred over that shown in Figures 1 and 2 because it eliminates substantially all possibilities of error creeping in in the setting or adjustment of the cutting blades in the cutter head. It is comparatively easy to grind flat surfaces so that they match each other and in the form of the invention shown in Figures 3 to 5 inclusive, advantage is taken of this. The cutter head is 55 ground so that one of its side faces is flat and the blade is so shaped and ground that it has a flat base surface adapted to rest against the flat side face of the head with the consequence that a cutting blade which has been ground to 60 a predetermined pressure angle on the relieving 65 grinder will not be tilted when positioned on the cutter head and the finished cutter will have the true pressure angle.

ing grinder will not be tilted when positioned on the cutter head and the finished cutter will have the true pressure angle.

The cutter head 50 which may be provided with a peripheral ring or shoulder 51 has one side face 52 ground absolutely plane or flat. A plurality of radial grooves 53 are formed in this side face of the cutter head and radial slots 54 are cut transversely through the head to communicate with the grooves 53. The cutter blades 55 have a cutting portion 56 and a foot or supporting portion 57 integral therewith.

The cutting portions of the blades may be of any usual or suitable construction. The cutter shown in Figures 3 to 5 inclusive is of the face mill hobbing type and the blades are formed according to the principles described in Patent No. 1,249,378 above mentioned. The blades 55 shown are adapted to cut alternately on opposite sides of the teeth.

The bottom or inside face 58 of the supporting portion 57 of each blade is ground so as to provide an absolutely plane or flat surface adapted to rest on the plane side face 52 of the cutter head and this supporting portion 57 is formed with a tongue 59 which is adapted to engage in the grooves 53 formed in the cutter head to guide the blade 55 in its radial adjustment on the cutter head.

In the form shown in Figures 3 to 5 inclusive, the blades are adjusted by screws 60 which are provided with heads 61 that engage in kerfs or recesses formed in the undersides of the tongues 59 of the blades and which thread each into another screw 62 which in turn threads into the ring 51 of the cutter head. The screw 60 is made with a different number of threads per inch from that of the screw 62. In one construction actually used the screw 60 had twenty threads per inch and the screw 62 nineteen threads per inch. As the screw 60 is held from turning by the head 61, one turn of the screw 62 will impart a movement to the blade 55 equal to the difference in the amount of lead of the two screws. Thus, the two screws 60, 62 form a differential screw device enabling a very accurate adjustment of the cutter blades to be made. Each of the blades is secured in any 100 adjusted position by means of bolts 64 which thread into the foot portions 57 of the blades and pass through the slots 54 in the cutter head.

With the side face 52 of the cutter head 120 ground flat and the inside face of the blades also ground flat, the blades will seat accurately on the cutter head and will not tilt when being secured thereto or adjusted thereon. As the blades are accurately ground in the 125 relieving machine, it will follow that the assembled cutter will cut accurately.

Figures 6 and 7 show a modification of the invention in which the principle of providing a flat surface on the cutting blade to seat 130

against a flat surface on the cutter head is also utilized. The difference between the modification shown in Figures 6 and 7 and that shown in Figures 3 to 5 inclusive is in the 5 means for adjusting the cutter blade in the cutter head.

In Figures 6 and 7, the cutter head is indicated at 70. Its side face 71 is ground plane and is formed with radial grooves 72. Radial 10 slots 73 are cut through the cutter head and communicate with the grooves 72. The blades 74 have their cutting portions 75 formed in any usual or suitable manner and their foot or supporting portions 76 are provided with 15 inside faces which are ground flat to rest on the side face 71 of the cutter head and are provided with tongues adapted to engage in the grooves 72 of the cutter head. This construction is the same as in the modification of 20 the invention shown in Figures 3 to 5 inclusive. The supporting portions 76 have a stud 77 formed integral therewith and adapted to extend through the slot 73 formed in the cutter head. Each of the blades 74 is adjusted 25 radially on the cutter head 70 by means of a screw 78 which threads through a nut 79 secured to the cutter head and into the stud 77 of the blade. The blade is secured in any adjusted position by means of the washer 80 and the nut 81 which threads onto the stud 30 77 of the blade.

In the modification illustrated in Figures 8 and 9, the principle of a flat surface on the blade resting against a plane side face on the head is again used. Here the cutter head is designated at 85. It is again provided with a plurality of radial grooves 86 and with transverse slots 87 communicating with these grooves. The cutter blades, of which 35 only one is shown, have cutting portions 88 and supporting portions 89. The supporting portions 89, as in the case of the blades illustrated in Figures 3 to 5 inclusive, have plane inside faces adapted to rest on the plane 40 side face 90 of the cutter head and have tongues adapted to engage in the grooves 86 of the cutter head to guide the blades in their radial adjustments on the cutter head.

Each of the blades is provided with an integral stud 91 which is adapted to extend through a slot 87 of the cutter head. Each blade can be adjusted in the cutter head 85 by means of the screws 92 and 93 which engage opposite sides of the stud 91. The 45 screw 93 is held against rotation by means of a pin 94 that engages in a slot 95 cut longitudinally in the screw and the screw threads into a nut 96 that is held between the side walls of a recess 97 cut into the cutter 50 head in alignment with the radial groove 86. Each blade is held in any adjusted position by means of the washer 98 and the nut 99 that threads onto the stud 91 of the blade.

Figures 10 and 11 show a further modification of the invention employing the principle

of a flat surface on the blade resting against a flat side face of the cutter head. 100 designates the cutter head. Its side face 101 is ground plane and is formed with a plurality of radial grooves 102. Radial slots 103 are cut transversely through the cutter head in alignment with the grooves 102. Only one of the cutting blades is shown. 104 designates the cutting portion of this blade and 105 the foot or supporting portion. The 10 foot portion 105 has its inside face 106 ground plane to rest on the side face 101 of the cutter head and is formed with a tongue 107 which is adapted to engage in a radial groove 102 of the cutter head to guide the blade in its 15 radial adjustment on the cutter head. The blade is formed with an integral stud 108 that extends through a slot 103 of the cutter head and the blades are adjustable by means of screws 109 and 110 which thread into the 20 cutter head and engage the stud 108 from opposite sides thereof. The screw 109 is recessed at its outer end to receive a suitable tool and the screw 110 is provided at its outer 25 end with a knurled head 111 which is received into a slot or recess 112 formed in the cutter head. Each blade is held in any adjusted position by means of a washer 113 and a nut 114 that threads on to the stud 108.

Figures 12 to 14 inclusive illustrate a further modification of this invention in which the principle of a flat surface on the blade engaging a flat side face of the cutter head is utilized. 120 designates the cutter head. It is provided with a plane side face 121 and this side face is formed at equi-spaced intervals with radial grooves 122 while radial slots 123 are cut through the cutter head 120 communicating with the grooves 122. The 125 blades are formed with cutting portions 125 and with foot or supporting portions 126. In the cutter shown, the cutting portions are all arranged on a circle according to the manner of Patent No. 1,236,834 above referred to and the blades are all outside cutting blades, each blade having an outside cutting edge. It is to be understood throughout this specification that the invention is 130 independent of the form of the cutting portion and that each modification is applicable whether the cutter be constructed for employment in an intermittent indexing operation or in a continuous indexing operation and whether the blades have one or two cutting edges and whether that one cutting edge be an inside or an outside cutting edge.

The supporting portion 126 of each blade has its inside face plane to match the side face 121 of the cutter head and is formed 135 with a tongue 127 which is adapted to engage in a groove 122 of the cutter head. The blade has an integral stud 128 adapted to pass through a slot 123 of the cutter head. Radial adjustment of the blade is effected by 140

means of screws 129 and 130. The screw 129 threads into the cutter head and engages the stud 128 on one side thereof. Each screw 130 threads into the cutter head for movement 5 transversely thereof and is provided with a conical inner end 131. This inner end 131 is adapted to engage the beveled end of a pin 132 which engages at its other end the stud 128 at a point diametrically opposite to the 10 point of engagement of the screw 129 with the stud. It will be seen that by unthreading the screw 129 and by threading up the screw 130, the pin 132 will be moved to adjust the cutter blade in one direction and by reversing 15 these operations, the blade can be adjusted in the opposite direction. Each blade is secured in any adjusted position by means of the washer 134 and nut 135, the latter threading onto the stud 128.

20 The idea of providing a plane surface on the blade supporting member to seat against a plane side face of the cutter head and thereby prevent tilting of the blade in its adjustment on the cutter head, is used in the 25 modification of the invention illustrated in Figures 15 and 17 inclusive but here the supporting member is not integral with the blade but is constructed as a separate part to which the blade is secured. 140 designates the cutter head. It is provided with a plane ground side face 141 and is formed with a plurality 30 of radial T-slots 142.

Each cutting blade 143 is secured to a supporting member 144 by a screw 145. The inside faces 146 of the supporting members are 35 ground plane to seat against the side face 141 of the cutter head. The supporting members are, also, recessed on their inside faces as indicated at 147 to receive the upper end of 40 T-blocks 148. A block 148 is secured to each supporting member 144 by a screw 149 and a dowel pin 150. The T-blocks 148 are adjustable radially of the cutter head in the T-slots 142 by means of a differential screw device 45 comprising the screw 151 which threads into the T-block 148 at one end and into another screw 152 at the other end, the latter screw 152 threading into the cutter head.

50 Instead of providing a socket or slot in the periphery of each supporting member 144 into which to seat the cutting blade 143, it is deemed preferable to grind the periphery of the supporting member 144 as part of a conical surface and grind a conical surface on the 55 inside of the cutting blade. The conical surface on the blade is so ground, preferably, as to undercut the blade below its cutting portion, as clearly shown in Figure 17 and provide a shoulder 155 which is adapted to seat 60 against the upper face of the supporting member 144 when the screw 145 is threaded home. The conical surfaces of all the inside or outside blades of a cutter head can be ground simultaneously, thus all the blades will be 65 alike and it is possible also, to grind the

conical surfaces on all the supporting members simultaneously. Hence when the blades are assembled on the head they will all have exactly the same pressure angle.

Figure 18 illustrates another modification 70 of the invention in which the supporting member is separate from the cutting blades and in which the inside face of the supporting member is ground plane to seat against a ground side face of the cutter head. 160 75 designates the cutter head. It is provided with a plane side face 161 and formed with a plurality of radial T-slots 162. Each blade 163, as before, is preferably provided with a conical surface to seat against a correspondingly shaped conical surface 164 ground on the periphery of the supporting member 165 and the shoulder 166 formed on the blade rests against the outer face of the supporting member. Each blade is secured to its supporting member by a screw 167. The supporting members 165 as in the case of the supporting members 144 have their inside faces ground plane to seat against the side face 161 of the cutter head but the supporting members 165 are formed with integral T-shaped portions engaging in the T-slots 162 of the cutter head. Each supporting member 165 is adjusted radially on the cutter head to adjust the corresponding cutter blade 90 radially of the cutter head by a screw which threads at one end into the T-shaped portion of the supporting member and at its other end into another screw 169 that threads into the cutter head. The two screws form a 100 differential screw device permitting of a fine adjustment. A lock-nut 170 may be provided to thread onto the screw 168 to secure it in any adjusted position, while the bolt 172 and nut 173 assists in securing the blade in its 105 adjusted position.

Figures 19 to 21 inclusive illustrate a further modification of this invention employing supporting members separate from the cutting blades. 180 designates the cutter 110 head. It is formed with a plane side face 181 and with a plurality of radial grooves 182. 183 designates the cutting blade and 184 the supporting members therefor. Here the cutting blades are secured on the inside 115 periphery of the supporting members instead of on the outside periphery thereof as in previously described modifications. This serves to illustrate further the scope of this invention. The inside peripheral surface 186 120 of each supporting member is ground conically and the inside face of each blade 183 correspondingly ground and the blades formed with shoulders adapted to seat on the outside faces of the supporting members. Each blade is secured to its supporting member by a screw 187. The supporting members 184 have their inside faces 188 ground plane to seat against the side face 181 of the cutter head and are formed with 130

grooves 189. Blocks 190 and 191 which are secured in the groove 182 of the cutter head by dowel pins 192 and 193 engage in the groove 189 of each supporting member 184 and serve to guide the supporting member 184 in its radial adjustment on the cutter head.

No special means has been illustrated for adjusting the supporting members 184 on the cutter head and it will be understood that 10 any of the means heretofore described or any other suitable means may be employed for this purpose or that the cutter truing fixture may be arranged so as to effect this 15 adjustment. Each supporting member 184 is secured in any adjusted position by means of a screw 195 that threads into the cutter head 180 and a washer 196 which engages the supporting member 184. Preferably, the 20 supporting member 184 is recessed, as indicated at 197 to receive the head of the screw 195 and the washer 196.

Figures 22 to 24 inclusive illustrate a further embodiment of the invention. Here, 25 200 indicates the cutter head which has a plane side face 201 and is formed with a plurality of radial grooves 202. In each of the grooves 202, there is secured a block 203 by means of a dowel pin 204. 205 designates 30 the cutting blade and 206 the supporting member to which the blade is secured by means of a screw 207. The supporting member 206 is, preferably, provided with a conical peripheral surface 208, as in the preceding embodiment, and the cutting blade 205 is formed with a correspondingly shaped inside face adapted to seat against the peripheral face 208 and with a shoulder 209 adapted to seat on the outer face of the supporting member 206 when the blade is secured 40 to the supporting member.

The supporting member has its inside face 210 ground plane to match the side face 201 of the cutter head against which it seats and 45 the supporting member 206 is formed with a groove 211 in which the block 203 is adapted to engage to guide the supporting member 206 in its radial adjustment on the cutter head. This radial adjustment may be effected in any suitable manner. The supporting member 206 is secured in any adjusted position by means of screws 212 which pass through the supporting member, one on either side of the groove 211 and thread into 50 the cutter head 200 on either side of the tongue or block 203. The supporting member 206 is preferably recessed as shown at 215 and 216 in Figure 23 to receive the heads of the screws 212 and the washers 217.

60 Other modifications of the invention are possible as will be clear to those skilled in the art to which the invention pertains. In general, it may be said that the invention is capable of various further modifications and uses and that this application is intended to

cover any variations, uses, or adaptations of the invention following, in general, the principles of the invention and including such departures from the present disclosure as come within known or customary practice 70 in the art to which it pertains and as may be applied to the essential features hereinbefore set forth and as fall within the scope of the invention or the limits of the appended claims. 75

Having thus described my invention, what I claim is:

1. A gear cutter comprising a rotatable head having a radial groove formed therein and a radial slot communicating with said groove and having a plane side face, a blade having a cutting portion projecting beyond the adjacent side face of the head in the direction of the axis of the head and a supporting portion formed with a plane face adapted to seat on the plane face of the head and with a tongue engaging in said groove and having a stud which passes through said slot connected to said supporting portion, said cutting portion having a side-cutting edge, means for adjusting the blade radially on the head and means adapted to be secured to said stud for holding the blades in any adjusted position. 80

2. A gear cutter comprising a rotatable head having a radial groove formed therein and a radial slot communicating with said groove and having a plane side face, a blade having a cutting portion projecting beyond the adjacent side face of the head in the direction of the axis of the head and a supporting portion formed with a plane inside face adapted to seat on the plane face of the head and with a tongue engaging in said groove and having a stud connected to said supporting portion which passes through said slot, said cutting portion having a side-cutting edge, means engaging said stud for adjusting the blade radially on the head, and means secured to the stud for holding the blade in any adjusted position. 90

3. A gear cutter comprising a rotatable head having a radial groove formed therein and a radial slot communicating with said groove and having a plane side face, a blade having a cutting portion projecting beyond the side face of the head in the direction of the axis of the head and a supporting portion formed with a plane inside face adapted to seat on the plane face of the head and with a tongue engaging in said groove and having a stud connected to said supporting portion which passes through said slot, said cutting portion having a side-cutting edge, a pin engaging said stud having a beveled outer end, a screw for adjusting the blade radially on the head, said screw being threaded into the head transversely thereof and having a tapered nose engaging the bevel of said pin, 115 120 125 130

and means for securing the blade in any adjusted position.

4. A gear cutter comprising a rotatable head having a radial groove formed therein and a radial slot communicating with said groove and having a plane side face, a blade having a cutting portion projecting beyond the adjacent side face of the head in the direction of the axis of the head and a supporting portion formed with a plane inside face adapted to seat on the plane face of the head and with a tongue engaging in said groove and having a stud connected to said supporting portion which passes through said slot, said cutting portion having a side-cutting edge, and a screw threaded into said head and engaging said stud for adjusting the blade radially on the head.

5. A gear cutter comprising a rotatable head having a plane side face and formed with a plurality of radial slots, a plurality of blades, each of which has a seating portion, the underside of which is plane and is adapted to rest against the plane side face of the head, a cutting portion extending from said seating portion beyond the adjacent side face of the head in the general direction of the axis of the head and having a side cutting edge which is inclined to the axis of the head, and a shank-portion which engages in and passes through one of the slots of the head, means engaging the shank-portion of each blade and movable in the head for adjusting the blade radially in the head, and means for securing each blade in position after adjustment.

6. A gear cutter comprising a rotatable head having a plane side face and formed with a plurality of radial slots, a plurality of blades, each of which has a seating-portion, the underside of which is plane and rests against the plane side face of the head, a cutting portion extending from said seating-portion beyond the adjacent side face of the head and having a side-cutting edge inclined to the axis of the head, and a cylindrical shank-portion which engages in and passes through one of the slots of the head, and means engaging the shank portion of each blade and movable in the head for adjusting the blades radially in the head, and means for securing each blade in position after adjustment.

7. A gear cutter comprising a rotatable head having a plurality of radial slots formed therein, a plurality of removable cutter blades, each blade having a shank-portion which passes through one of the slots of the head, and a cutting portion, which, when the blade is in position on the head, extends beyond the adjacent side face of the head in the direction of the axis of the head and provided with a side cutting edge which is inclined to the axis of the head, means for

engaging the shank portion of each blade and movable in the head for adjusting the blade radially in the head, and means for securing each blade in position after adjustment.
